UNITED STATES PATENT OFFICE.

FRANCESCO LAMBERTI, OF GENOA, ITALY.

ROTARY MOTOR.

1,009,534.

Specification of Letters Patent. Patented Nov. 21, 1911.

Application filed June 30, 1910. Serial No. 569,828.

To all whom it may concern:

Be it known that I, FRANCESCO LAMBERTI, professor, a subject of the King of Italy, residing at 19 Via Palestro, Genoa, in the 5 Kingdom of Italy, manufacturer, have invented a certain new and useful Centrifugal Expansion Rotatory Motor for an Expansible Fluid, of which the following is a specification.

10 This invention relates to improvements in rotary motors.

The object of the invention is to provide a rotary motor in which the full power of the steam is utilized before the exhaust 15 occurs.

The invention depends on two principles, one of which may be termed the "principle of intercepted outlet turnstile" and the other the "principle of centrifugal expansion."

20 Figures 1, 2, and 3 embody these principles and represent the hypothetical apparatus in longitudinal and transverse section. Fig. 4 is a longitudinal section of a rotary motor constructed in accordance with this invention. Fig. 5 is a transverse section of a portion of the apparatus. Fig. 6 is a longitudinal section of a portion of the apparatus. Fig. 7 is a transverse section taken on the 25 line 7—7 of Fig. 6. Fig. 8 is a longitudinal section of a slightly modified form of motor. Fig. 9 is a transverse section taken on the line 9—9 of Fig. 8. Fig. 10 is a longitudinal section of still another form. Fig. 11 30 is a detail sectional view of the rotary distributing valve.

In the embodiment illustrated in Figs. 1, 2, and 3, a receptacle R is mounted on a pivot A' and an axle A. This axle A forms 40 a conduit between a pipe H and the receptacle R and is designed to convey a fluid from a source not shown. The axle A is movably mounted in a bearing c and the pivot A in a bearing c'. A canal F opens 45 through the periphery of the receptacle R and may be of any suitable or desired length and is constructed substantially in the form of a flattened pipe. A pipe T is bent in spiral form and fixed to the receptacle R 50 with its inner end I ending in the opening or canal F. A plurality of diaphragms D are disposed successively in the canal F and are maintained in fixed position by arms b, fixed to a rod J secured to a bracket K 55 fixed in the proximity of the interior end of

the hole or canal F, and ending where the system turns at an angle d, see Fig. 3, at which point the diaphragm is disposed in proximity to the outer end of the canal which is near to the end of the tube I. Suppose, for example, that every diaphragm after having occupied the position above described and after the succeeding diaphragm D' held fixed by the arm d' began to operate, the preceding diaphragm of the interior end 60 of the hole or canal F disappears, it is evident that if I then introduce the operating fluid into the receptacle R upon the internal wheel, such fluid will cause the rotation of the system. In consequence of this rotation, the fluid will be introduced into the pipe T in successive quantities corresponding to the circumscribing volumes through the hole F by means of two consecutive diaphragms. This manner of operation of the fluid 65 comprises the "principle of the intercepted outlet turnstile." The principle termed "centrifugal expansion" is dependent upon the action of the fluid in the pipe T after the beginning of the rotation of the system and 70 of the fluid discharged from said pipe T through its other end into a receptacle suitably disposed to receive it. The diaphragms D and D' and the successive diaphragms 75 form means suitable for intercepting the fluid outlet from the receptacle R and at the same time for regulating the fluid in the pipe and may be termed a "distributer."

In Figs. 4 and 5 of the drawings is represented an industrial application of the invention with regard to the above named principles. In this embodiment a hollow axle A is shown similar to the axle of Figs. 1, 2, and 3, and is incorporated with the rotary portion of the engine and is held by a bearing c which is provided with a stuffing box or other analogous device adapted to prevent the escape of the fluid around the axle. A pivot shaft A' carries the turning part of the motor and is arranged in a bearing c' in alinement with the axle A, the two bearings being carried by the supporting structure of the motor. A pipe H connects the hollow axle A with the fluid channel not shown having a regulating valve V. The turning portion of the motor has a space S therein and is provided with a curb joint C containing a pipe t. This joint C is preferably composed of two disks between which is fixed a spirally turned plate having an 100 105 110

inlet I and an outlet U. Similar curbs C' and C'' are spaced laterally from the curb C and any desired number of said curbs may be employed.

5 The curb C is provided with a distributing apparatus shown in detail and on an enlarged scale in Figs. 6 and 7, longitudinal and transverse sections of said apparatus being shown in these figures. This distributing apparatus comprises a box which turns jointly with the motor curbs and a fixed member F of cylindrical contour termed a nucleus. A plurality of diaphragms D are also arranged within the 10 box. The box of this apparatus has substantially a cylindrical form on its outer face and its inner face co-operates with the cylindrical contour of the nucleus and the tubular space t. An annular cam G operates with the fixed member F and is provided with an inner cam face g which engages the nucleus. During the turning 15 of the box the cam ring G frictionally engages the member F at the points f-f and the nucleus is held by the pivots p-p mounted in bearings supported by the member G and it is fixed by means of a rod j which extends through the member G and is provided with a stuffing box and is fixed 20 to the motor in any suitable manner, preferably by means of arms K. Within the tubular space T one of the diaphragms D is continuously acting serving to form a transverse closure for said tubular space. 25 These diaphragms D are forced outwardly as shown in Fig. 8 to form spaces d around the nucleus and when so projected to form closures for the tube t and they are afterward drawn into said spaces d to permit 30 the member G to rotate. In these Figs. 6 and 7 are shown four diaphragms intercepting successively the space t during a quarter turn of the motor. Each pair of these diaphragms is connected by a rod or link l and 35 motion is imparted to said diaphragms by means of a cam b carried by a secondary axle a which turns with the box. This cam b operates upon rollers r which are fixed to the connecting links l. The axle a and the 40 cam b together with the rollers r are disposed within the nucleus which for this reason is made hollow. The diaphragms D may be projected by means of the cam on the inner face of the box if necessary but 45 they are preferably actuated by the cam b in the manner above described. The box is preferably provided with two openings c and c' the opening c affording a connection between the space S and one end of the 50 tube t, while the opening c' affords communication between the other end of the tube t and the pipe I of the curb C. R and R' are designed to receive the fluid and 55 precede the curbs C' and C''. Peripheral plates M and M' incase the receivers R and

R' and a fixed casing N contains the turning portion of the motor and is provided with an outlet pipe P.

In the operation of this improved motor, the operating fluid from a suitable channel (not shown) enters through the valve V into the passage or pipe H and is conducted through the hollow axle A into the space S of the motor. From this space S the fluid passes through the opening c into the tube t and operates in the manner above described relative to the principle of the turnstile intercepted outlet. After passing through the pipe t the fluid is discharged through an opening o onto the curb C and from there passes out through the outlet U and expands successively into the curb C' and C'', passing respectively through the receivers R, R' between these curbs. In these curbs the fluid acts on the principle of the centrifugal expansion above described.

In the apparatus shown in Fig. 4 the passage of the fluid through the motor is clearly illustrated, the arrows indicating the passage from the outlet of one curb to the inlet of the succeeding curb and from the outermost curb C'' into the casing N and out through the outlet P therein into the atmosphere or any suitable receptacle into which it is desired to pass.

The operation of the diaphragm D is clearly illustrated in Figs. 8 and 9 in which the cavity or space d within the nucleus are arranged in such a manner that said diaphragm operates therein by means of the connecting links l which pass through the nucleus and engage said diaphragms.

In Fig. 8 the inner face of the member G is provided with two tubular channels e and e' which extend concentrically with the axle and are adapted to contain the fluid under different pressures. Such pressures may be obtained by placing the channels e and e' in communication with the fluid under different pressure or by depressing the members G and F in such a manner that the fluid will pass out from i and enter between said members and pass into the channels e and e' and be discharged into a space in which little pressure is exerted. For example, by discharging through the interior cavity of the nucleus and the rod j, which is also hollow. By means of suitable spaces k and k' formed in member G and communicating with the channels e and e' respectively, and of conduits h and h' which lead into the cavities d of the member F, some of the operating fluid may be opportunely introduced into the cavity d and be discharged upon every pair of diaphragms to facilitate their motion. A hollow rod j may be provided to lubricate the pivots p and p', the axle a and cam b, the rods or links l and the diaphragms respectively.

In Fig. 10 all of the curbs C, C' and C'' are provided with a distributing apparatus and the nucleus F, F' and F'' are joined together in fixed relation by a rod *j* and the boxes G, G' and G'' are connected with the curbs and the axle *a* turning jointly with the curbs carrying the cams *b*, *b'* and *b''* which impart motion to the distributing diaphragms. This form of motor is similar 10 to the one above described, except the operating fluid passes from the outlet of one curb to the inlet of the succeeding curb through the distributing apparatus.

When desired a number of pipes or tubes 15 may be employed and in Fig. 11 the box G is shown to be adapted for use when two tubes *t* are employed.

From the foregoing description, taken in connection with the accompanying drawings, the construction and operation of the 20 invention will be readily understood without requiring a more extended explanation.

Various changes in the form, proportion 25 and the minor details of construction may be resorted to without departing from the principle or sacrificing any of the advantages of the claimed invention.

I claim as my invention:

1. A rotary motor driven by expansible 30 pressure medium and having a spirally bent passage open at its ends and arranged to form a motor element, the pressure medium coming into action from one end to the other of said passage, distributors arranged in

said spiral passage to serve as rotary motors 35 the rotary parts thereof rotating independently on and together with the actual motor and the fluid flowing from said distributors into said spiral passage.

2. In a rotary engine operated by an expansive fluid, curbs arranged in said engine, a box mounted to turn with said curbs, a fixed nucleus, a tubular conduit arranged to discharge into one of said curbs and diaphragms intercepting successively the fluid 45 introduced into said conduit.

3. In a combined turbine and engine of the class described having consecutive spiral passages, cylindrical plates arranged between said passages and rotating with the 50 spirals to form intermediate spaces and being completely contained in the rotating part, said spaces serving to convey the fluid from one of said spiral passages to the next.

4. In a rotary engine operated by an expansive fluid, curbs arranged in said engine, a box mounted to turn with said curbs, a fixed nucleus, a tubular conduit arranged to discharge into one of said curbs and diaphragms intercepting successively the fluid 60 introduced into said conduit, a cam turning jointly with said curbs and means connecting said cam with said diaphragms for actuating the latter.

F. LAMBERTI.
